UNITED STATES PATENT OFFICE

2,547,709

MOTOR-GENERATOR GEARING

Everett P. Larsh, Dayton, Ohio

Application September 24, 1945, Serial No. 618,227

7 Claims. (Cl. 74—810)

1

This invention relates to an electrodynamic device and more particularly to an electrodynamic device that may be used either as a motor or as a generator.

It is well known in electrical theory that a dynamo or generator may be used as a motor and vice versa. However, for some purposes it has not been considered feasible to use one unit both as a generator and as a motor, in spite of the fact that the two may not be used simultaneously. An illustration of this is the generator and starter motor used in starting an internal combustion engine, whether the engine be a low compression engine or a high compression engine. In the automobile industry a generator separate and distinct from the starter is generally used. This applies to larger types of engines, as for example, Diesel engines. The use of a generator separate from the starter motor obviously increases the cost of production, adds weight and also multiplies the parts that may get out of order and require repairs.

An object of this invention is to provide an electrodynamic device that functions as a motor when starting an internal combustion engine and functions as a generator after the engine starts.

Another object of this invention is to provide an electrodynamic device that functions both as a motor and as a generator for starting an engine and for charging a storage battery et cetera, which electrodynamic device rotates at a relatively high speed as compared with the speed of the engine when starting the engine and rotates at the same speed as the engine when functioning as a generator.

Another object of this invention is to provide an electrodynamic device that functions as a generator and as a motor, wherein the relative speed of the electrodynamic device with respect to the speed of the motor changes when the electrodynamic device shifts its function from that of a starter to that of a generator.

Another object of this invention is to provide a planetary gear system for interconnecting an electrodynamic device to a motor, which planetary gear system automatically changes the relative speed between the electrodynamic device and the motor when the electrodynamic device ceases to function as a starter motor and changes over to a generator.

Another object of this invention is to provide an electrodynamic device with conductors that extend beyond the rotor, which conductors function as commutator segments.

2

Another object of this invention is to provide a commutator wherein the centrifugal force exerted upon the commutator segments is counteracted by a force pushing against the commutator segments so as to prevent a radial displacement thereof.

Another object of this invention is to provide a commutator wherein the commutating surface is positioned inwardly to permit the brush holders and the brushes to be located within the commutator.

Another object of this invention is to provide an annular member into which the commutator segments are press-fitted, the annular member surrounding the commutator segments, thereby preventing radial displacement thereof when the commutator segments are subjected to the influence of centrifugal force.

Another object of this invention is to provide a generator and a starter motor in a single unit, thereby eliminating expensive duplication of parts such as shafts, bearings, rotors, stators, commutators, housings and other parts.

Another object of this invention is to provide means for alternating the usage of a rotor both as a driving member and as a driven member or as a starter and as a generator.

Another object of this invention is to provide mechanical operating means for multiplying and transmitting the armature torque to an engine crankshaft.

Another object of this invention is to provide a variable speed changing mechanism wherein the same gears are utilized in transmitting power at more than one speed ratio without shifting gears.

Another object of this invention is to provide a commutator wherein the commutator bars are formed from extensions of the armature conductors.

Another object of this invention is to provide sealing means for a lubricant wherein the gasket is squeezed so as to force it against the surface to be sealed to seal the opening.

Another object of this invention is to provide an electrodynamic device functioning both as a generator and starter motor incorporated into a single unit, having the rotor mounted upon the crankshaft of the engine to be started, so that the rotor may transmit power to the crankshaft or the crankshaft may transmit power to the rotor.

Another object of this invention is to provide an electrodynamic device functioning as a generator and as a starter motor having the armature

mounted on the shaft of the engine to be started and connected thereto by an overrunning clutch or ratchet, so as to allow the armature to drive said shaft for starting purposes and to be driven by said shaft for generating purposes.

Other objects and advantages reside in the construction of parts, the combination thereof and the mode of operation, as will become more apparent from the following description.

Referring to the drawings, Figure 1 is a cross sectional view taken substantially on the line 1—1 of Figure 2.

Figure 2 is a fragmentary cross sectional view taken substantially on the line 2—2 of Figure 1.

Figure 3 is an enlarged fragmentary cross sectional view disclosing the pawl for governing the movement of the planetary gear system.

Figure 4 is a fragmentary cross sectional view taken substantially on the line 4—4 of Figure 1.

Figure 5 is a fragmentary cross sectional view of a portion of a commutator taken substantially on the line 5—5 of Figure 1.

Figure 6 is a schematic showing of a modification disclosing a planetary gear system wherein the orbital gears are provided with radially disposed weights.

In the drawings, the reference character 20 indicates the end of the crankshaft of an internal combustion engine. The internal combustion engine may be a Diesel type engine or ignition type engine or any other suitable internal combustion engine. The end of the shaft 20 is mounted in a suitable bearing 22, having mounted thereon a tubular sleeve 24. The sleeve 24 is so mounted that it may rotate with respect to the shaft 20. The sleeve 24 has mounted thereon an armature or rotor 25 that includes a collar 26, having mounted thereon an annular ring 28 providing a support for armature laminations 30, held in position by upset edges 32 of the annular ring 28. Each slot in the laminations 30 supports two windings 40. Each winding consists of a copper bar and has a substantially U-shaped contour. One leg of each U-shaped member is seated in the bottom of a slot and the other leg is seated in another slot and positioned on top of a corresponding winding. In the trade these windings are oftentimes referred to as hairpin windings. The loop ends 42 of the windings 40 are all positioned on one side of the armature or rotor. In the past, it has been common practice to solder or fuse the free ends of the hairpin windings to commutator segments. This is the practice that is followed by at least some of the automobile manufacturers in connection with starters.

In the device disclosed herein, the ends of the hairpin windings project outwardly from the slots in a substantially straight line. As may best be seen by referring to Figure 5, the ends 40a and 40b of the windings are mounted contiguous to a tapering copper bar or segment 44 contacting a strip of insulating material 46, functioning as a spacer member. A ring of insulating material 50, such as mica, surrounds the ends of the windings 40, the copper segments 44 and the insulating spacer members 46. A suitable steel ring 52 surrounds the ring of insulating material 50.

In order to secure a rigid assembly, the armature, together with the ends of the hairpin windings, the copper bar 44 and the insulating material, are subjected to a sub-zero temperature, so as to shrink or contract the parts. The ring 52, on the other hand, is heated, so as to cause it to expand. The commutator bars are held in a pig that may be displaced by suitable increments from

time to time while the steel ring 52 is press-fitted into position. By this arrangement, the commutator segments and the steel ring constitute a rigid press-fitted assembly, wherein the commutator segments, consisting of the ends 40a and 40b and the copper bars 44, cannot spread outwardly in response to centrifugal force.

The interior of the commutator segments are trimmed or machined, so as to form a smooth internally located commutating surface. The insulating spacer members 46 may be undercut, so as to provide the conventional grooves found between commutator segments.

A reenforcing and centering ring 58, having an L-shaped cross sectional area, is fixedly attached to the rotor and has one leg 58a contacting a suitable ring of insulating material abutting the interior of the commutator segments, so as to hold the commutator segments concentrically with respect to the center of rotation of the armature. Instead of L-shaped cross sectional area, the reenforcing and centering ring may have any other suitable cross sectional area.

Brush holders 60, supporting suitable brushes 62, urged radially and outwardly by springs 64, mounted upon brackets 66, contact the inner surface of the commutator segments. The brush holders 60 are secured by suitable screws 68 to annularly mounted insulating segments 70 attached to a suitable end frame or end bell 72 fixedly attached to a stator housing 74, carrying pole pieces 76, shown schematically.

When the electromagnetic device is used as a motor in starting an internal combustion engine or supplying power to any other suitable device, the rotor of the motor rotates at a much higher speed than the crankshaft of the engine to be started. When the electrodynamic device functions as a generator, it rotates at the same speed as the crankshaft. This variation in speed ratios has been accomplished by the use of a planetary gear system wherein the spider is held stationary when the electrodynamic device functions as a motor and wherein the orbital gears are locked so as to cause the spider to rotate at the same speed as the crankshaft and the rotor when the electrodynamic device is used as a generator. The details of the planetary gear system will now be described.

The planetary gear mechanism is mounted between the end frame 78 and the frame 80 of the internal combustion engine. The planetary gear system includes a pinion 82 fixedly attached to the tubular sleeve 24 for rotation with the rotor. The pinion 82 meshes with orbital gears 84, each attached to a flanged sleeve portion 86 integral with a pinion 100 journalled on a bearing 88 mounted on a pintle 90 and held in position by a washer 92 seated in a suitable groove in the end of the pintle 90. The pintle 90 is attached to a thimble 94 welded to a spider 96. The function of the spider 96 will be described more fully later. The pinion 100 meshes with a gear 102 fixedly attached to the hub of a cogged wheel 104 keyed to the shaft 20. The relative speed ratio between the rotor 25 and the shaft 20 is dependent upon whether or not this spider 96 is locked for non-rotary movement or is free to rotate when the gears are locked.

As may best be seen by referring to Figure 3, the spider control mechanism includes a dog or a pawl 110 mounted upon a pivot 112 mounted in lugs 114 fixedly attached to the periphery of the spider 96. The end 110a of the dog or pawl 110 is heavier than the end 110b. A suitable spring 111

is used to rotate or bias the dog or pawl 110 in a counterclockwise direction, as viewed in Figure 3. When this dog or pawl is in the horizontal position shown in Figure 1, the end 110a is seated in a suitable notch 116 in a ring 118 welded to tongues or projections 120 formed from the end frame 78. As may best be seen in Figures 1, 3 and 4, a ring 122 is mounted between the ring 118 and the end frame 78. This ring 122 is provided with inclined extensions or projections 122a that function to eject the end 110a from the notch 116 whenever power is supplied from the engine to the armature. When the end 110a is in contact with the notch 116 in ring member 118, ring members 118 and 122, together with the spider 96, rotate in unison. This takes place when the starter drives the engine. When the engine starts it soon accelerates, causing a relative movement between the spider 96 and the ring 122. This causes the rings 118 and 122 to move in a counterclockwise direction relative to members 110a, as viewed in Figure 4, causing the inclined surface 122a to actuate the weighted ends 110a outwardly against the force of the spring 111. When the end 110a is forced outwardly, this spider will begin to spin, causing the end 110a of the dog or pawl to be thrown outwardly by centrifugal force, so as to cause the end 110b of the pawl to engage teeth 130 located in the side of the gear 84. When the end 110b of the pawl is seated in these notches, the gear 84 cannot rotate with respect to the spider and when the gear 84 cannot rotate with respect to the spider, this spider must of necessity rotate in unison with the shaft 20. In so doing, the armature 25 rotates at the same speed as the crankshaft. The ring 122 may be adjusted relative to the ring 118 so as to cause the end 110a to drop into engagement with the opposite side of the notch.

The adjustment of the ring 122 is moved in unison with a suitable switching mechanism that has not been shown, for reversing the direction of rotation of the armature 25. Thus, by this arrangement, it is possible to crank the engine in either direction. By reversing the relative direction of the flux generated by the stator field and that generated by the armature, the direction of rotation of the armature may be reversed, as is well known to those skilled in the art. One of these magnetic fields may be reversed by reversing the current through one of the windings. The switching mechanism for reversing the current from one of the windings is preferably connected to the actuating mechanism connected to the ring 122 for actuating this ring from one position to the other.

In order to confine the lubricants to the proper cavities, a ring 131 is located between the hub of the spider and the bearing 132 in the end frame 78. A grease seal or oil seal is attached to the end of the shaft 20 and includes a pair of disc-like members 140 and 142 clamping a resilient member 144, made of neoprene or other suitable material, that may be used as an oil seal. The discs 140 and 142 are held in position by a suitable screw 146 that may be tightened to squeeze the ring 144 against the wall of the cylindrical cavity 148 in the end of the tubular member 24.

In the modification disclosed in Figure 6, a schematic illustration of the orbital gears in the planetary gear system has been shown. A pinion 200 is driven by the armature and meshes with a plurality of orbital gears 202 mounted for rotation on pintles 204 attached to a suitable spider that has not been shown. Each of the gears 202

has been provided with a weight 206, the weights at all times being equally spaced from the axis of rotation of the pinion 200, the axis of the orbit of the orbital gears. By this arrangement, the weights 206 do not tend to produce an unbalanced condition as far as the orbital center is concerned. When the electrodynamic device functions as a starter, the spider stands still while the orbital gears rotate about their respective axis 204.

- 10 As soon as the engine starts, so as to transmit power, the spider begins to rotate in a manner similar to that described in connection with the preferred embodiment. As soon as the spider begins to rotate, the weights 206 have a tendency to retard the rotary movement of the orbital gears 202, in that the weights 206 will tend to move outwardly radially with respect to the spider supporting the orbital gears 202 into the position shown in Figure 6. As soon as the centrifugal force exerted upon the weights 206, by virtue of the rotation of the spider about the shaft 20, is greater than the torque tending to rotate these gears, the gears 202 will remain stationary with respect to the spider, thereby causing the spider to rotate in unison with the pinion 200 and with the crankshaft of the engine.
- 15 The spider may be locked in position when starting the motor in a manner similar to that disclosed in connection with the preferred embodiment. Instead thereof, an overrunning clutch arrangement may be used to hold the spider stationary while starting the generator. When starting the generator, the spider tends to rotate in one direction. When the engine starts and the engine begins to drive the electrodynamic device, the force exerted upon the spider is in the opposite direction, thereby releasing an overrunning clutch. Instead of one overrunning clutch, a pair of overrunning clutches may be used, one for locking the spider when starting the engine in one direction and the other for locking the spider when starting the engine in the opposite direction. Whenever the engine is to be started, only one of the clutches is engaged, the other remaining disengaged until the time arrives for starting the engine in the opposite direction.

- 20 The two legs of the windings located in the same slot are separated by insulating material throughout their entire length within the slot. The ends 40a and 40b, projecting beyond the slots, need not be separated by insulation. The insulation between the ends 40a and 40b is preferably eliminated, so as to insure a better electrical contact.
- 25 Although the preferred embodiment discloses an internal commutating surface, the external surface could be used as a commutating surface by merely rearranging the insulating ring 50 and the iron ring 52, so as to provide a clearance for the brushes. Instead of one external ring, it might be feasible to use two external rings for holding the bars in position. The commutating surface could then be between the two rings.
- 30 Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. An electrodynamic device adapted to func-

tion as a generator and as a starter for an internal combustion engine having a crankshaft, the combination including a bearing mounted on the end of the crankshaft, a rotor journaled on the bearing, a planetary gear system including gears for interconnecting the rotor to the crankshaft so that the planetary gear system interconnects the rotor to the crankshaft, said planetary gear system including a spider mounted for rotation, and means for arresting the rotation of the gears when the crankshaft attains a predetermined speed so as to cause the electrodynamic device to function as a generator.

2. A duo-functional electrodynamic device used as a starter and as a generator for an internal combustion engine having a crankshaft, the combination including a stator, a rotor, the rotor being concentrically mounted with respect to the crankshaft, a change speed gear mechanism for interconnecting the rotor to the crankshaft, said change speed gear mechanism including a planetary gear system having gears for transmitting motion from the rotor to the crankshaft and vice versa, said planetary gear system including a rotatably mounted spider, and means for arresting the rotation of the gears when the crankshaft of the engine attains a predetermined speed so as to cause the electrodynamic device to function as a generator.

3. A duo-functional electrodynamic device used as a starter and as a generator for an internal combustion engine having a crankshaft, the combination including a stator, a rotor, the rotor being concentrically mounted with respect to the crankshaft, and a planetary gear system for interconnecting the rotor to the crankshaft, said planetary gear system including a pair of solar gears one of which is larger than the other, one of the solar gears being connected to the rotor and the other to the crankshaft, a plurality of sets of orbital gears, each set including two interconnected gears one of which meshes with the one solar gear and the other meshes with the other solar gear, a spider rotatably mounted on an axis concentric with the axis of rotation of the rotor, said orbital gears being mounted for rotation on the spider, means for locking the spider in stationary position when the electrodynamic device functions as a starter, and means for locking the orbital gears with respect to the spider when the electrodynamic device functions as a generator.

4. A duo-functional electrodynamic device used as a starter and as a generator for an internal combustion engine having a crankshaft, the combination including a stator, a rotor, the rotor being concentrically mounted with respect to the crankshaft, and a planetary gear system for interconnecting the rotor to the crankshaft, said planetary gear system including a pinion rigidly connected to the rotor, a second pinion keyed to the crankshaft, orbital gears having one gear meshing with the first pinion and a second gear meshing with the second pinion, said orbital gears being interconnected, a spider mounted for rotation about an axis concentric with the axis of rotation of the rotor, said spider supporting the orbital gears, means for locking the spider so as to hold it stationary when the electrodynamic device functions as a starter, and means for releasing the spider and locking the orbital gears with respect to the spider when the electrodynamic device functions as a generator so as to cause the rotor to rotate in unison with the crankshaft.

5. A duo-functional electrodynamic device used

as a starter and as a generator for an internal combustion engine having a crankshaft, the combination including a stator, a rotor, the rotor being concentrically mounted with respect to the crankshaft, and a planetary gear system for interconnecting the rotor to the crankshaft, said planetary gear system including a pinion rigidly connected to the rotor, a second pinion keyed to the crankshaft, orbital gears having one gear meshing with the first pinion and a second gear meshing with the second pinion, said orbital gears being interconnected, a spider mounted for rotation about an axis concentric with the axis of rotation of the rotor, said spider supporting the orbital gears, spring-urged means for locking the spider in stationary position when the electrodynamic device functions as a starter, and centrifugal means for releasing the spring-urged means to release the spider so as to permit it to rotate with the rotor when the electrodynamic device functions as a generator.

6. A duo-functional electrodynamic device used as a starter and as a generator for an internal combustion engine having a crankshaft, the combination including a stator, a rotor, the rotor being concentrically mounted with respect to the crankshaft, and a planetary gear system for interconnecting the rotor to the crankshaft, said planetary gear system including a pinion rigidly connected to the rotor, a second pinion keyed to the crankshaft, orbital gears having one gear meshing with the first pinion and a second gear meshing with the second pinion, said orbital gears being interconnected, a spider mounted for rotation about an axis concentric with the axis of rotation of the rotor, said spider supporting the orbital gears, and means responsive to centrifugal force for arresting the rotation of the orbital gears with respect to the spider when the electrodynamic device functions as a generator.

7. A duo-functional electrodynamic device used as a starter and as a generator for an internal combustion engine having a crankshaft, the combination including a stator, a rotor, the rotor being concentrically mounted with respect to the crankshaft, and a planetary gear system for interconnecting the rotor to the crankshaft, said planetary gear system including a pinion rigidly connected to the rotor, a second pinion keyed to the crankshaft, orbital gears having one gear meshing with the first pinion and a second gear meshing with the second pinion, said orbital gears being interconnected, a spider mounted for rotation about an axis concentric with the axis of rotation of the rotor, said spider supporting the orbital gears, and means for locking the spider so as to hold it stationary when the electrodynamic device functions as a starter, said last mentioned means including a ratchet mechanism having a pair of rings one of which is notched and the other having inclined teeth, said rings having a relative movement so as to reverse the direction of the ratchet mechanism.
